U. INSUA

KEY

Filed Sept. 17, 1925

FIG.1.

FIG.2.

Inventor

Urbano Insúa

By Emil Bönnelycke
Attorney

UNITED STATES PATENT OFFICE.

URBANO INSÚA, OF CAMPANA, ARGENTINA.

KEY.

Application filed September 17, 1925, Serial No. 56,996, and in Argentina June 15, 1925.

My present invention relates to certain improvements in keys, its main object being to provide a new form of key composed of two or more elements capable of being easily put together, which key can only be used when all its elements are assembled.

The present invention has been clearly shown in the appended drawings by way of example, although it is to be clearly understood that it is in no way limited to the specific form shown and that it may be applied to all kinds and types of keys.

In the said drawings, Figure 1 is a front view of a key according to my present invention and Figure 2 is an edge view of the same.

According to my present invention the key is formed of two portions or sections *a* and *b* which may be placed one into the other to form when assembled, a complete key which can only be used when in this condition. It will be observed that the outer member *a* embodies an open or skeleton head and a bifurcated or longitudinally slotted shank; and that the inner member *b* embodies head and shank portions which fit conformably in the head opening and bifurcation or slot of the outer member, respectively. Both members lie wholly in a common plane and have their shanks provided at their free outer ends with suitable wards, the shank on the inner member pro-

jecting axially beyond the outer end of the bifurcation or slot of the outer member.

Each section of the key according to my present invention may be kept by different persons, so that in order to open or close the corresponding lock, the presence of all these persons will be necessary, which gives a great security and control, particularly in the case of keys for safes or the like.

Having now fully described and ascertained the nature of my present invention and in what manner the same is to be carried into practice, I declare that what I claim and desire to protect by Letters Patent is:

1. A key, comprising an outer member embodying an open or skeleton head and a longitudinally slotted shank; and an inner member embodying head and shank portions which fit, respectively, in the opening in the head and the slot in the shank of the outer member; both members lying wholly in a common plane and having their shanks provided at their free outer ends with wards.

2. A key, according to claim 1, in which the shank of the inner member projects axially beyond the outer end of the slot in the shank of the outer member.

In testimony whereof I affix my signature.

URBANO INSÚA.
